MULTIPLE CLAMP FOR LITHOGRAPHIC
PLATE GRAINING MACHINES

Martin G. Dunn, Washington, D. C.

Application January 6, 1947, Serial No. 720,389

10 Claims. (Cl. 51—6)

This invention relates to improvements in lithographic plate graining machines, and more particularly to hold-down devices for clamping the plates firmly and evenly upon the bottom of the grainer box or tub.

The general object of the invention is to provide a novel and improved plate clamping device for graining machines by means of which the edges of a number of plates may be clamped in position for graining by pursuing a minimum of manual operations.

Another object of the invention is the provision of a novel multiple grainer clamp of the class described which can be quickly applied and released, which is resilient in operation, and which is easy to manufacture and install while at the same time being of sturdy construction and not liable to get out of order or to require frequent repair or replacement.

In its preferred embodiments, the invention contemplates the provision of a plurality of spring pressed hold-down feet disposed in rows across the grainer tub and preferably in alignment with the clamp-supporting cross bars which span the tub at intervals along the length thereof. The clamping feet associated with one of the cross bars are all operatively connected with an elongated actuating bar or frame which is disposed for limited vertical movement adjacent the cross bar, and manually operated levers are arranged to raise and lower the clamp supporting frames in order to release and apply the several clamps to the plates.

By means of this novel arrangement, a plurality of clamps may be released and applied by the manipulation of one or two levers and the time of operation of the graining process much reduced.

Other objects and features of novelty will be apparent from the following specification when read in connection with the accompanying drawings in which certain embodiments of the invention are illustrated by way of example.

In the drawings:

Figure 1 is a view in perspective of one end of the graining machine tub embodying the principles of the invention;

Figure 2 is a fragmentary vertical sectional view taken on line 2—2 of Figure 1, one of the presser feet or clamps being shown in raised or released position;

Figure 3 is a similar view showing the foot in depressed or operative clamping position;

Figure 4 is a fragmentary view in vertical section taken along the clamp bar approximately on

line 4—4 of Figure 2; the released position of the parts of the clamp, however, being shown in broken lines;

Figure 5 is a fragmentary perspective view of an end of the tub of a plate graining machine, showing another embodiment of the invention; and

Figure 6 is a fragmentary vertical sectional view taken approximately along the center line of the clamp bar assembly.

The grainer box or tub forming the basis of the embodiment illustrated in Figures 1 to 4 of the drawings is indicated in the drawings by the reference numeral 10, and it will be understood by those skilled in the art that the tub 10 is mounted in a substantially horizontal position for rotary or gyratory movement in the horizontal plane. Means are also provided for loading the tub, after the lithographic plates are properly clamped therein, with the steel balls or marbles and the wetted abrasive material, as is also well known in the art. The tub 10 is provided with an end wall 11, side walls 12, and a bottom wall 13 upon which is secured the rubber blanket 15. A wooden strip 16 is secured along the inside of the lower portion of the side and end walls and to this strip is secured the marginal strip of rubber 17.

Lithographic plates 20 which are to be grained are laid in orderly rows upon the blanket 15 upon the bottom of the tub, and are adapted to be firmly retained in flat position to be acted upon by the abrasive under the influence of the rolling balls or marbles. These plates are of any familiar type, whether made of zinc, copper, or aluminum, or whether new or used. The object of the graining process is to prepare clean grained surfaces on the plates for the reception of the lithographic image in the process of lithographic or offset printing. In the case of the treating of old plates, the object is to remove the old image from the surface of the plate so that the plate may be used over and over again.

Although the hold-down clamp may be applied directly to the corners or margins of the plates 20, it is preferred to cover the marginal edges of the plates with the hold-down strips 22 which are preferably made of thin flexible material and provided with bevelled or chamfered edges so that the balls may roll freely across their surfaces as well as upon the working surfaces of the plates being treated.

The clamping arrangement comprises generally a series of cross bars or frames 25 which span the tub at intervals along the length thereof, and

are secured to the turned flanges 26 of the side walls 12 for adjustment therealong. The flanges 26 are preferably cut away adjacent the end of the tub so that the clamp frame may be more readily removed when necessary.

The clamping bar or frame assembly comprises basically the pair of spaced angle irons 28 having down-turned vertical flanges and inwardly directed horizontal flanges 29. At each end of the pair of bars 28 there is secured, as by welding, a short transverse angle piece 30, the outer edge of the horizontal flange of which abuts the inner edge of the side wall flange 26 of the tub, and serves to aid in guiding the adjusting movement of the clamp frame. To the vertical flange of the angle piece 30 at each end of the frame, is welded the projecting jaw plate 31 through an opening in which is threaded the set screw 32. It will be understood that the angle pieces 28 overlie the tub flange 26 and the flange is received between the angle pieces 28 and the overlying projection 31. The set screw or bolt 32 serves to rigidly secure the clamp frame to the flange 26 in its adjusted position above the margins of the plates 20 in the tub.

Within the slot between the flanges 29 of the angle irons 28, there are disposed at suitable intervals the clamps 35, each of which comprises a flat foot portion 36 which is adapted to bear upon the plates 20 or the strips 22, and a stem portion 37 which extends through the slot between the flanges 29. Surrounding each of the stems 37 is a coil spring 38 which is compressed between the edges of the flanges 29 and a cotter pin 39 passing through an opening in the stem 37. A washer 40 may be provided to afford a better spring seat adjacent the edges of the flanges 29. The spring 38 thus continually urges the clamp element 35 downwardly toward the plates. To accommodate the clamping arrangement to plates of varying dimensions, the clamps 35 may be moved along the frame 25 to any desired position.

In order to raise the clamps 35 from contact with the plates 20 or the strip 22, as for removal of the finished plates and the positioning of new plates to be treated, an actuating means is provided which includes a pair of spaced angle irons 42 between the vertical flanges of which the upper ends of the stems 37 project. A cotter pin 43 extends through an opening in the upper end of each stem 37 and bears upon the upper edges of the vertical flanges of the angles 42. At two spaced points along the angles 42 pivot pins or bolts 44 are provided. These pins pass through the vertical flanges of the angles 42 and through a lever arm 45. At appropriate points along the frames 25, bearing plates 47 are provided, these plates being secured as by welding to the under side of the flanges 29 of the angles 42. The plates 47 are adapted to be contacted by the lower ends 48 of the levers 45, and it will be readily understood that upon rocking the levers 45 the end 48 will bear upon and slide along the plate 47 and the pin 44 will be raised, thus lifting the actuating subframe comprised by the angles 42.

The lifting of this actuating sub-frame 42, through the cotter pins 43, will lift each one of the clamp elements 35, the principal parts of the device being shown in raised position, in broken lines in Figure 4 of the drawings. The angle irons 42 of the lifting frame are rigidly connected together adjacent their ends by the blocks 46 which serve to connect their vertical flanges. Although two hand levers 45 are provided it is conceivable that one lifting lever could be provided

at the center of the frame, although such an arrangement might not be as satisfactory as the use of two levers.

An important feature of the lever arrangement is illustrated to best advantage in Figure 4 of the drawings. It will be noted that the spacing and dimensioning of the various parts, particularly the lever 45 and the stem 37 of the clamps 35, is such that when the parts are in applied position, 10 the levers 45 will contact both the plate 47 as at 50 and the top of the stem 37 as at 51. In this way the weight of the adjusting subframe is utilized to bear upon the presser clamps 35 when they are applied to the plates, and there is 15 a minimum of lost motion between the operative parts which would produce rattling during the vigorous oscillation of the tub.

In Figures 5 and 6 of the drawings, there is 20 illustrated another embodiment of the invention in which a modified clamping frame is employed. The various parts of the tub and plate arrangement will be given the same reference numerals as in the preceding embodiment. The alternative clamp supporting frame, however, is designated generally by the reference numeral 125.

The relatively fixed part of the clamp frame 125 comprises the channel member 128 the ends of which rest upon the opposite side wall flanges 26 of the tub. Plates 129 are secured as by 30 welding to the under sides of the ends of the channels 128 and form a lower jaw for receiving the tub flange 26. A set screw 132 serves to fix the channel 128 in adjusted position along the tub. Openings 130 are provided at intervals in the base flange of the channel 128 for the reception of the stems 137 of the presser plates 136 of the clamp 135 adapted to bear upon the photographic plates 20 or the hold-down strips 22.

The coil spring 138 surrounds each stem 131 and is seated at its upper and lower ends against the lower surface of the channel 128 and against the cotter pin 139 respectively.

The lifting subframe in this embodiment comprises the inverted channel 142 which fits within the flanges of the base channel 128. Openings 141 are formed in the base flange of the channel 142 and register with openings 130 in the channel 128 and are adapted to receive the stems 137 of the clamps 135. Cotter pins 143 pass through the upper ends of the stems 137 and bear upon the top surface of the operating channel bar 142. At one or two points along the channel 142 slots 146 are provided for the reception of the lower ends of the operating levers 145. Ears 152 are 50 provided at each side of the slot 146 and a pivot pin or bolt 144 passes through registering openings in ears 152 and in the lever 145.

The lower end 148 of the lever bears against the upper surface of the bottom flange of the channel 128 and is adapted to move along this surface when the lever is swung to raise or lower the lifting frame. In Figure 6 of the drawings the principal parts are shown in solid lines in clamping position and in broken lines in released 65 or raised position, and the operation of this form of the invention will be readily understood therefrom. As a lever 145 is swung from its solid line position the pin 144 is raised and this causes the lifting frame or bar 142 to rise, carrying with it the stems 137 of the clamps 135, and the clamps are thereby released from pressure upon the plates 20.

Various changes and modifications may be made in the embodiments illustrated and described herein without departing from the scope

of the invention as defined by the following claims.

Having thus described the invention, what is claimed as new and desired to be secured by Letters Patent is:

1. In a lithographic plate graining machine, a grainer tub, an elongated clamp supporting frame secured to and extending across and above the tub in spaced relation to the bottom thereof, a plurality of plate clamps carried by said frame, each of said clamps including a presser foot adapted to exert bearing pressure upon a plate resting upon the bottom of the tub, means for resiliently urging said feet downwardly toward said plates, and means for simultaneously raising said clamps from and lowering them to clamping position.

2. In a lithographic plate graining machine, a grainer tub, an elongated clamp supporting frame secured to and extending across and above the tub in spaced relation to the bottom thereof, a plurality of plate clamps carried by said frame, each of said clamps including a presser foot adapted to exert bearing pressure upon a plate resting upon the bottom of the tub, means operatively engaging said feet and said supporting frame for resiliently urging said feet downwardly toward said plates, an elongated actuating sub-frame operatively connected with all of said plate clamps, and manual operating means for raising and lowering said sub-frame and thus the clamps which are connected thereto.

3. In a lithographic plate graining machine, a grainer tub, an elongated clamp supporting frame secured to and extending across and above the tub in spaced relation to the bottom thereof, a plurality of plate clamps carried by said frame, each of said clamps including a presser foot adapted to exert bearing pressure upon a plate resting upon the bottom of the tub, means operatively engaging said feet and said supporting frame for resiliently urging said feet downwardly toward said plates, an elongated actuating sub-frame operatively connected with all of said plate clamps, and means carried by said sub-frame adjacent each end thereof and operatively associated with said supporting frame and adapted to be simultaneously manually actuated to raise and lower said clamps.

4. In a lithographic plate graining machine, a grainer tub, a plate clamping assembly secured to said tub for adjustment along the tub and spanning the tub in spaced relation to the bottom thereof, said assembly comprising an elongated base frame, a plurality of vertically movable plate clamps, and a clamp actuating sub-frame; means for guiding said clamps past said base frame during their raising and lowering movements, connections between said sub-frame and each of said clamps, means whereby the sub-frame is raised and lowered relative to said base frame and the associated clamps moved from operative position to released position.

5. In a lithographic plate graining machine, a grainer tub, a plate clamping assembly secured to said tub and spanning the tub in spaced relation to the bottom thereof, said assembly comprising an elongated base frame, a plurality of vertically movable plate clamps each comprising a vertical stem and a presser foot, and a clamp actuating sub-frame; means for guiding said clamp stems past said base frame during their raising and lowering movement, resilient means which bear against said clamps and said base frame to urge the clamps downwardly toward plate clamping

position, connections between said sub-frame and each of said clamps, and at least one lever operatively connecting the sub-frame and said base frame.

5. In a lithographic plate graining machine, a grainer tub, a plate clamping assembly secured to said tub and spanning the tub in spaced relation to the bottom thereof, said assembly comprising an elongated base frame, a plurality of vertically movable plate clamps each comprising a vertical stem and a presser foot, and a clamp actuating sub-frame; means for guiding said clamp stems past said base frame during their raising and lowering movement, coil springs surrounding said stems and bearing against said clamps and said base frame to urge the clamps downwardly toward plate clamping position, connections between said sub-frame and each of said clamps, and at least one lever pivoted to one of the frames and adapted to cam against the other frame whereby the sub-frame is raised and lowered relative to said base frame and the associated clamps moved from operative position to released position.

25. In a lithographic plate graining machine, a grainer tub, a plate clamping assembly secured to said tub and spanning the tub in spaced relation to the bottom thereof, said assembly comprising an elongated base frame; a plurality of vertically movable plate clamps each comprising a vertical stem and a presser foot, and a clamp actuating sub-frame; means for guiding said clamp stems past said base frame during their raising and lowering movement, resilient means which bear against said clamps and said base frame to urge the clamps downwardly toward plate clamping position, connections between said sub-frame and each of said clamps, at least one lever operatively connecting the sub-frame and said base frame; said base frame comprising a pair of angle shapes spaced apart for the reception of the clamp stems therebetween, said sub-frames also comprising angle shapes spaced apart to receive the upper portions of said stems, mutual abutting portions 40 on each stem and the sub-frame for connecting said stems and said sub-frame at least during their upward movement, and pivot pins passing through said levers and said vertical flanges of the sub-frame, an end of each of said levers 45 adapted to bear upon a surface of said base frame.

8. In a lithographic plate graining machine, a grainer tub, a plate clamping assembly secured to said tub and spanning the tub in spaced relation to the bottom thereof, said assembly comprising an elongated base frame, a plurality of vertically movable plate clamps each comprising a vertical stem and a presser foot, and a clamp actuating sub-frame; means for guiding said clamp stems past said base frame during their raising and 55 lowering movement, resilient means which bear against said clamps and said base frame to urge the clamps downwardly toward plate clamping position, connections between said sub-frame and each of said clamps, at least one lever operatively connecting the sub-frame and said base frame; said base frame comprising a pair of angle shapes having vertical flanges and horizontal inwardly directed flanges spaced apart for the reception of the clamp stems therebetween, said sub-frames 60 also comprising angle shapes having outwardly extending horizontal flanges and spaced adjacent vertical flanges spaced apart to receive the upper portions of said stems, stop elements for connecting said stems and said sub-frame at least during 65 their upward movement, pivot pins passing

through said levers and said vertical flanges of the sub-frame, an end of each of said levers adapted to bear upon a surface of said base frame.

9. In a lithographic plate graining machine, a grainer tub, a plate clamping assembly secured to said tub and spanning the tub in spaced relation to the bottom thereof, said assembly comprising an elongated base frame, a plurality of vertically movable plate clamps each comprising a vertical stem and a presser foot, and a clamp actuating sub-frame; means for guiding said clamp stems past said base frame during their raising and lowering movement, resilient means which bear against said clamps and said base frame to urge the clamps downwardly toward plate clamping position, connections between said sub-frame and each of said clamps, at least one lever operatively connecting the sub-frame and said base frame; said base frame comprising a pair of angle shapes having vertical flanges and horizontal inwardly directed flanges spaced apart for the reception of the clamp stems therebetween, said sub-frames also comprising angle shapes having outwardly extending horizontal flanges and spaced adjacent vertical flanges spaced apart to receive the upper portions of said stems, stop elements for connecting said stems and said sub-frame at least during their upward movement, pivot pins passing through said levers and said vertical flanges of the sub-frame, the parts being so constructed and arranged that when in lowered operative position, the outer manipulative portion of the lever bears upon the upper end of an adjacent clamp stem, while the lower end bears against a camming surface of the base frame, and thus causes the weight of the sub-frame and levers to assist in exerting downward force upon the clamps, and minimizes lost motion and rattling during operation.

10. In a lithographic plate graining machine, a grainer tub, a plate clamping assembly secured to

said tub and spanning the tub in spaced relation to the bottom thereof, said assembly comprising an elongated base frame, a plurality of vertically movable plate clamps each comprising a vertical stem and a presser foot, and a clamp actuating sub-frame; means for guiding said clamp stems past said base frame during their raising and lowering movement, resilient means which bear against said clamps and said base frame to urge the clamps downwardly toward plate clamping position, connections between said sub-frame and each of said clamps, at least one lever operatively connecting the sub-frame and said base frame; said base frame comprising a channel bar having openings at intervals in its web for the reception of the clamp stems, said sub-frame comprising an inverted channel adapted to be received within the flanges of the channel forming the base frame when in lowered position, openings in the web of said sub-frame through which the upper ends of the clamp stems extend, stop means carried by the upper end of said stems for operatively connecting them to said sub-frame, one or more openings in the web of said sub-frame to accommodate an operating lever and means for pivoting said lever to said sub-frame adjacent an opening, one end of said lever adapted to cam against the web of said base frame when actuated, the opposite end of the lever adapted for manual actuation.
